UNITED STATES PATENT OFFICE.

GUSTAVE E. GRUNDSTROM, OF CHICAGO, ILLINOIS, ASSIGNOR OF ONE-HALF TO JOHN W. ION, OF CHICAGO, ILLINOIS.

POWER MOLDING-PRESS.

1,072,448.

Specification of Letters Patent.

Patented Sept. 9, 1913.

Application filed February 8, 1912. Serial No. 676,435.

To all whom it may concern:

Be it known that I, GUSTAVE E. GRUNDSTROM, a citizen of the United States, and a resident of the city of Chicago, county of 5 Cook, and State of Illinois, have invented certain new and useful Improvements in Power Molding-Presses, of which the following is a specification.

My invention relates to improvements in 10 power molding presses, and has for its object the provision of a press of this character which shall be of simple construction and efficient in operation.

The invention consists in the combinations and arrangements of parts hereinafter described and claimed.

My invention will be best understood by reference to the accompanying drawings forming a part of this specification, and in 20 which—

Figure 1 is a perspective view of a press embodying my invention, Fig. 2, a side elevation of said press shown partially in section, and Fig. 3, a vertical section taken 25 through the operating cylinder of said press.

The preferred form of construction, as illustrated in the drawings, comprises a suitable table 1 supported on a suitable frame 30 or standard 2. Secured to one side of frame 2 is an upwardly extending standard 3 having a substantially U-shaped frame 4 pivoted to the upper end thereof. Frame 4 carries a lug 5 adjacent the pivotal point and 35 a spring 6 is secured to the outer end of lug 5 and to the lower portion of standard 3 at 7, as shown. The other limb of frame 4 carries a pivoted catch arm 8 provided at its lower end with a nose 9 adapted to en- 40 gage under the corresponding side of frame 2. Arm 8 is provided with handles 10 and a spring 11 serves to hold said arm in normal engagement with the under side of an edge of frame 2.

An operating cylinder 12 is mounted centrally on top of frame 4, said cylinder being open at the bottom and provided with an upwardly extending guide well 13 at the top. A piston 14 operates in cylinder 12 50 and carries a hollow threaded stem 15 extended to operate in well 13 and also to project downwardly from cylinder 12. A threaded rod 16 is adjustably mounted in stem 15 and carries at its lower end a pressure plate 17 by means of which pressure 55

may be applied to a mold on table 1. A spring 18 is interposed between piston 14 and the top of frame 4 and serves to hold piston 14 normally in elevated position. A three-way valve 19 is secured to the top of frame 4 and connected by means of a pipe 20 with the upper portion of cylinder 12, said valve serving as a means for supplying and exhausting compressed air to and from the upper portion of cylinder 12, as 60 will be readily understood by those skilled in the art.

In use, when it is desired to apply pressure to a mold on table 1, compressed air is admitted through valve 19 to the upper portion 70 of cylinder 12. This forces piston 14 and consequently pressure plate 17 downwardly to apply such pressure. By adjusting rod 16 in stem 15, pressure plate 17 may be adjusted to different heights of molds. 75 When it is desired to relieve the pressure, three-way valve 19 is turned to exhaust cylinder 12 whereupon spring 18 will raise pressure plate 17 from contact with the mold. Then, by releasing catch arm 8, 80 frame 4 may be swung upwardly and rearwardly entirely out of the way, for the removal of one mold and the replacement of another. Then the parts may be readily restored to operative position by swinging frame 4 over table 1 and engaging catch arm 8 with the edge of frame 2, as explained 85 above. During the return movement of frame 4, spring 6 will serve to yieldingly resist such movement and thus prevent 90 shocks and jars, lug 5, besides furnishing a convenient anchor for one end of spring 6, also serves to limit the upward and backward swing of frame 4.

The construction set forth will be found 95 to be simple and economical to build and efficient in use, the parts not readily becoming broken or out of order and sand from the molds not readily getting into the different bearings.

While I have illustrated and described the 100 preferred form of construction for carrying my invention into effect, this is capable of variation and modification without departing from the spirit of the invention. I, 105 therefore, do not wish to be limited to the exact details of construction set forth, but desire to avail myself of such variations and modifications as come within the scope 110 of the appended claim.

Having described my invention, what I claim as new and desire to secure by Letters Patent, is:

In a device of the class described, a table, 5 a support spanning said table and hinged to one side thereof, a press on said support, and a spring catch on the free end of said support for engagement with said table below the top thereof, the top of said table

being unobstructed, substantially as described.

In testimony whereof I have signed my name to this specification in the presence of two subscribing witnesses.

GUSTAVE E. GRUNDSTROM.
